US00D806066S

(12) **United States Design Patent** (10) **Patent No.:** **US D806,066 S**
(45) **Date of Patent:** **** Dec. 26, 2017**

(54) **ELECTRONIC DEVICE**

- (71) Applicant: **Amazon Technologies, Inc.**, Seattle, WA (US)
- (72) Inventors: **Giles David Matthew McWilliam**, San Francisco, CA (US); **Sun Joo Han**, San Francisco, CA (US); **Gregory Michael Hart**, Mercer Island, WA (US); **Christopher Green**, San Francisco, CA (US); **Marc Rene Walliser**, San Francisco, CA (US)
- (73) Assignee: **Amazon Technologies, Inc.**, Seattle, WA (US)

(**) Term: **15 Years**

(21) Appl. No.: **29/562,671**

(22) Filed: **Apr. 27, 2016**

(51) **LOC (10) Cl.** **14-02**

(52) **U.S. Cl.**

USPC **D14/314**

(57) **CLAIM**

The ornamental design for an electronic device, as shown and described.

DESCRIPTION

FIG. 1 is a bottom front perspective view of a first embodiment of an electronic device showing our new design; FIG. 2 is a top back perspective view thereof;

FIG. 3 is a front view of FIG. 1;

FIG. 4 is a back view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a bottom front perspective view of a second embodiment of an electronic device showing our new design;

FIG. 10 is a top back perspective view of FIG. 9;

FIG. 11 is a front view of FIG. 9;

FIG. 12 is a back view of FIG. 9;

FIG. 13 is a left side view of FIG. 9;

FIG. 14 is a right side view of FIG. 9;

FIG. 15 is a top plan view of FIG. 9; and,

FIG. 16 is a bottom plan view of FIG. 9.

The broken lines immediately adjacent to the claim, represent the bounds of the claimed design while all other broken lines are directed to environment; the broken lines form no part of the claimed design.

1 Claim, 16 Drawing Sheets
